UNITED STATES PATENT OFFICE.

FENWICK D. FADER, JOHN TIBB, AND JOHN WILFRED TIBB, OF VANCOUVER, BRITISH COLUMBIA, CANADA.

CALL-REGISTERING TELEPHONE.

1,106,501.

Specification of Letters Patent. Patented Aug. 11, 1914.

Application filed September 19, 1913. Serial No. 790,667.

To all whom it may concern:

Be it known that we, FENWICK D. FADER, JOHN TIBB, and JOHN WILFRED TIBB, citizens of the Dominion of Canada, residing at 5 Vancouver, in the Province of British Columbia, Canada, have invented certain new and useful Improvements in Call-Registering Telephones, of which the following is a specification.

10 This invention relates to a telephone instrument having provision within it for registering a call whenever the central operator connects the user to the phone with which he desires to speak, by which means the user 15 of a phone may be charged strictly according to such use, instead of, as at present, paying a flat rate or on the basis of a record kept by the central operator and checked or not by the user.

20 The invention also comprises a provision whereby when a certain number of calls is exceeded the phone is automatically disconnected from the telephone circuit and cannot be re-connected except by a properly authorized person.

25 The phone is used in conjunction with a plug box which is permanently connected to the telephone circuit in which box is the actuating mechanism of the register and the 30 means for transmitting the registering movement to the registering mechanism of the phone, which is removably connected to the plug box whenever the phone is to be used.

35 The invention is particularly described in the following specification, reference being made to the drawings by which it is accompanied, in which:

40 Figure 1 is a face view of the interior of the plug box, the cover being removed. Fig. 2 is a vertical section on the line A—A of Fig. 1 through the plug box with the cover in position. Fig. 3 is a view of the telephone transmitter and receiver as connected together for portability when not in use. Fig. 4 is a longitudinal section through the telephone transmitter and the automatic call register showing the protecting cap detached, and Fig. 5 is a cross section of the 45 same on the line B in Fig. 4.

50 In these drawings 2 represents a call box which forms a permanent attachment in a room or building, to which box the wires 6 and 7 of the telephone system are connected 55 at the terminals 4 and 5 and are conducted

within the box. There is also a terminal 8 for the attachment of the grounding wire 9.

Within the box 2 is an electromagnet 10, the coil of which is in circuit between one of the terminals 4 of the telephone system 60 and the terminal 8 of the ground wire 9. The armature 11 of this electromagnet is on the end of one arm 12 of a bell crank lever 12—14 which is pivotally mounted at 13 on an attachment to the box 2, and this armature 11 is normally held out of contact by a light spring 16 between one side of the box and the armature, which spring holds the armature against a stop 17 projecting outward from the back of the box. The end of 70 the shorter arm 14 of the bell crank is formed as a segment with teeth, which mesh with those on the outside of a plug socket member 15 which is rotatably mounted on suitable insulation within the box 2. The socket 18 of the member 15 is provided with driving serrations to engage and rotate a corresponding tapered plug of the telephone call register to be described later. The metal socket member 15 is electrically connected 80 by a wire 19 to the terminal 4 of the telephone circuit.

The cover 3 of the call box is furnished with an apertured socket 20 which is in axial alignment with the socket member 15 85 and on one side of this socket 20 is a contact member 21 which is electrically connected by a wire 22 with the terminal 5 of the telephone circuit.

The telephone transmitter 25 is mounted 90 on one end of a hollow casing 26, the other end of which casing is designed to fit the socket 20 of the call box cover 3. Rotatably mounted in the smaller end of this hollow casing 26 and supported in a suitably 95 insulated end bearing 27 within it, is a stem 28, which stem projects through the end and has secured on it a contact plug 29 which is provided with longitudinal driving serrations corresponding with those of 100 the socket 18 of the socket member 15. Within the casing 26 this stem 28 is threaded to receive an indicating nut 30 from which a pointer 31 projects into an elongated slot 32 through the side of the casing. 105

Secured on the stem 28 within the casing 26 is a ratchet wheel 33 the teeth of which are engaged by a small pawl 34 mounted on the end of the casing and having an end 35 projecting beyond its pivot, and adjacent to 110

this end 35 is a keyhole 36 through which a key may be inserted to lift the pawl from engagement with the teeth of the ratchet wheel. A light spring holds this pawl in 5 engagement with the ratchet wheel.

On the side of the end of the casing which is inserted in the socket 20 is a contact 37 designed to engage and form electrical connection between the telephone transmitter 10 and the contact 21 within the socket of the box. The contact 21 should project within the circle of the end of 26 which is inserted in 20 so that the contact itself will form a key to insure that the telephone is in 15 the correct position to insure contact.

Secured on suitable insulation on the cross bar 40, which supports the bearing plate 27 of the spindle 28, is a light resilient contact 41 which extends parallel with the axis of 20 the stem 28 and exercises a contact with the nut 30 as it travels along the screwed end of 28. This contact 41 is of such length that when the nut 30 has traveled to its extreme 25 limit it will be free from engagement with the contact.

The contacts 37 and 41 are electrically connected with the transmitter 25 and its receiver 45, which parts may be removably connected together by inwardly bent extensions 30 43 from the mouth plate of the transmitter.

In use, when the end of the telephone casing 26 is inserted in the aperture 20 of the call box 2 connection is made between the 35 terminals 4 and 5 of the telephone circuit through the telephone and its receiver by contact of 37 with 21 and 29 with 15, and a call is given to the operator at the central office. The operator, in response to this 40 call, connects the caller to the phone with which he desires to speak and by pressing a key or button at the central station closes the circuit via wire 6 and ground connection 9 to energize the magnet 10. Thus current 45 passes through the relay 10 and it is energized and attracts its armature 11 to it and through the bell crank lever 12-14 rotatably oscillates the plug socket member 15. This partial rotation of 15 is communicated 50 through the plug 29 and stem 28 and advances the indicating nut 30 a fractional distance along the screw, the pawl of the ratchet wheel holding the stem in the position to which it is moved when the telephone 55 is removed from the call box socket at the completion of the desired conversation. When the number of calls have been made for which that particular phone has been adjusted, the nut 30 has moved beyond 60 the range of the contact 41 and the telephone can no longer be used until a properly authorized person by means of a key inserted in the keyhole 36 releases the pawl 34 from engagement with the teeth of the ratchet wheel and rotates the stem 28 back-

ward to carry the indicating nut 30 to its starting point. The pointer 31 of the nut indicates to the user the general number of calls recorded and the nearness to the out-of-use limit.

The telephone transmitter and receiver may be of any approved pattern but will preferably be made small where they are required to be portable, and a guard cap 44 will be provided to fit on the end of the 75 telephone casing 26 to protect the projecting end of the stem 28 and its plug 29 from injury. Where not required to be portable as for general office use, the telephone may be slidably mounted on the call box so as to 80 be endwise movable in or out of the socket 20 of the call box.

With this arrangement of automatically recording the phone calls, call boxes may be 85 stationed in public places for the convenience of telephone users, so that any one having a phone of a portable form may insert it in the socket of any call box and be connected by the central office to the phones with which they desire to speak.

The general use of these phones will not only be convenient for the users but will save the telephone companies a very considerable amount of expense of collecting 95 accounts, as the cost of say five hundred calls is practically prepaid when a phone is issued which is good for that number.

To guard against the record of the phone being tampered with by unauthorized parties, who might, by inserting a key, release the pawl 34 and rotate the stem 28 backward, a seal may be impressed over the keyhole or the key may be of special design, and provision may be made by which, if there is any attempt to tamper with it, the 105 electrical circuit of the phone is broken.

Having now particularly described our invention, we hereby declare that what we claim as new and desire to be protected in by Letters Patent, is:

1. A recording telephone comprising the combination with a call box which is connected to the wires of the telephone system, means for removably connecting telephone system, means for removably connecting the telephone transmitter and receiver to the wires of the telephone system in the call box, means within the telephone set for recording each call, and means within the call box for mechanically operating the recording mechanism of the telephone set when a call is connected by the central office, said last named means including an operating lever mechanically connected to the recording mechanism and a lever actuating magnet adapted to be operated by current impulses in the wires of the telephone system substantially as shown and described.

2. A recording telephone, comprising the combination with a call box which is con-

- nected to the wires of a telephone system, means for removably connecting a telephone transmitter and receiver to the wires of the telephone system in the call box, means 5 within the telephone set for recording each call and means within the call box for mechanically operating the recording mechanism of the telephone when a call is connected by the central office.
- 10 3. A recording telephone, comprising the combination with a call box which is connected to the wires of a telephone system, of a mechanism within the box which is electrically operated by current through the ground wire, of a telephone set having a recording mechanism in it, means for removably connecting the telephone set to the wires of the telephone system, and means for mechanically connecting the operative mechanism within the box to the recording mechanism of the telephone set.
- 15 4. A recording telephone, comprising the combination with a call box which is connected to the wires of a telephone system, of a mechanism within the box which is electrically operated by a current through the ground wire, of a telephone set having a recording mechanism in it, means for removably connecting the telephone set to the 20 wires of the telephone system, means for mechanically connecting the operative mechanism within the box to the recording mechanism of the telephone set, and means co-operative with the recording mechanism 25 for automatically disconnecting the telephone circuit when a predetermined number of calls has been recorded.
- 30 5. A recording telephone comprising the combination with a call box to which the wires of a telephone system are connected, a relay within the box the coil of which is connected between one of the wires of the telephone system and the ground wire, means for deriving a mechanical movement from the 35 relay, a telephone having a recording mechanism within its case, means for removably connecting the telephone to the call box and for electrically connecting its circuit to that of the telephone system, means for mechanically connecting the relay mechanism within the box with the recording mechanism of the telephone and means for automatically disconnecting the telephone circuit when a definite number of calls has been recorded.
- 40 6. A recording telephone, comprising the combination with a call box to which the wires of a telephone system are connected, a relay within the box the coil of which is connected between one of the wires of the telephone system and the ground wire, a member 45 rotatably mounted within the box which member is electrically connected to one of the wires of the telephone system and mechanically oscillated from the relay, a 50 telephone having a rotatable call recording mechanism, means for removably connecting the telephone to the circuit of the telephone system, means for mechanically connecting the recording mechanism of the telephone to the rotatable member within the 55 call box and means for automatically disconnecting the circuit of the telephone when a stated number of calls has been recorded.
- 60 7. A registering telephone, comprising the combination with a call box to which the 65 wires of the telephone circuit and the ground wire are connected, said box having an apertured socket in its cover the side of which socket is electrically connected within the call box to one of the terminals of the 70 telephone system wires, a member rotatably mounted within the box in alinement with the apertured socket of the cover which member is electrically connected to the other terminal of the telephone system, means for 75 axially oscillating the rotatable member by the current of the telephone system, a telephone transmitter mounted on a hollow casing one end of which casing is adapted to fit the socket of the call box and has a contact connected to the transmitter which contact is designed to engage that within the 80 apertured socket of the call box, a stem rotatably mounted within the hollow casing of the telephone which stem projects through 85 the end of the casing and has provision for 90 electrically and rotatably engaging the rotatable member within the call box said stem being threaded within the casing to receive a nut correspondingly threaded, means for 95 preventing rotation of the stem in one direction, means preventing rotation of the nut, and a contact connected electrically to the 100 transmitter of the telephone which contact is designed to engage the nut of the stem 105 throughout a limited range of endwise movement of the nut.
- 110 8. A registering telephone, comprising the combination with a call box having an apertured socket in its cover and to which box the wires of the telephone circuit and the ground wire are connected, of a socket member rotatably mounted within the box in axial alinement with the apertured socket of the cover, means for oscillating this socket member by a current passing through the ground wire, a telephone transmitter, a hollow casing to which the transmitter is secured one end of said casing adapted to fit 115 the socket of the call box and having a contact connected in the transmitter circuit, which contact is designed to engage that of the apertured socket of the call box, a threaded stem rotatable in the end of the 120 hollow casing the end of which stem projects through the end of the casing and has provision to electrically and rotatably engage the socket member of the call box, a nut on the threaded end of the stem, means 125 for preventing rotation of this nut, means 130

for preventing rotation of the stem in one direction and a contact engaging the nut through a limited range of endwise movement which contact is electrically connected 5 in the transmitter and receiver circuit.

9. A recording telephone, comprising the combination with a telephone transmitter and receiver electrically connected, of a hollow casing on one end of which the transmitter 10 is secured, a contact in the outside of said casing electrically connected in the transmitter and receiver circuit, a stem rotatably mounted in the end of the hollow casing and projecting axially through that end 15 said stem within the casing being threaded, a nut fitting the thread of the stem, means for preventing rotation of the nut, means for preventing rotation of the stem in one direction, a contact electrically connected to 20 the transmitter and receiver circuit and engaging the stem nut through a limited range of endwise movement, a call box having an apertured socket adapted to receive the end of the telephone casing and means 25 within the call box electrically connected to the ground wire of the telephone system for partially rotating the stem of the inserted telephone.

10. A registering telephone, comprising a 30 relay inclosed within a suitable box which relay is in circuit between one of the wires of the telephone system and the grounding wire, a lever fulcrumed within the box one end of which lever is applied as an armature 35 to the relay and the other has a toothed segment meshing with the teeth of a rotatably mounted socket member said socket member being electrically connected to the same wire of the telephone system as the relay, means

for normally holding the relay armature out of contact with the pole of its core, a cover for the box having an apertured socket in 40 alignment with the axis of rotation of the socket member said socket having a contact which is electrically connected to the other wire of the telephone system, a hollow casing on one end of which the telephone transmitter is secured and the other end of which is adapted to fit the socket of the call box said end having a contact which is electrically connected to the transmitter of the telephone and is designed to engage the contact 45 in the socket of the call box, a stem axially mounted in the end of the telephone casing and projecting through that end which projected end is provided with a plug to fit the socket member of the call box and 50 rotatably engage it, said stem within the casing of the telephone being threaded to receive a nut and having a ratchet wheel, a pawl permitting rotation of the ratchet wheel in one direction only, a contact electrically connected to the transmitter of the telephone, which contact engages the nut 55 throughout a limited range of its endwise movement on the stem, means for preventing rotation of the nut and for indicating outside the telephone casing the endwise position of the nut on the screw.

In testimony whereof we affix our signatures in presence of two witnesses.

FENWICK D. FADER.
